UNITED STATES PATENT OFFICE.

HENRY R. SIEVERKROPP, OF RACINE, WISCONSIN.

ENGINE-STARTER.

1,253,287.

Specification of Letters Patent. Patented Jan. 15, 1918.

Application filed March 17, 1917. Serial No. 155,471.

To all whom it may concern:

Be it known that I, HENRY R. SIEVERKROPP, a citizen of the United States, and resident of Racine, in the county of Racine and State of Wisconsin, have invented certain new and useful Improvements in Engine-Starters; and I do hereby declare that the following is a full, clear, and exact description thereof.

10 My invention relates to new and useful improvements in engine starters, more particularly of that type embodied in Patent No. 1,162,410 granted to me Nov. 30, 1915.

It is primarily the object of my invention 15 to provide a starting mechanism which may be associated with an engine in a most ready and convenient manner, and it is further an object more particularly with respect to automobile engines to procure an economy of 20 structure by utilizing the fan shaft of the engine as part of the starting mechanism.

A still further object resides in the provision of a starting mechanism which is exceedingly compact in nature, and which may 25 be assembled and disassembled in a most ready manner.

With the above and other objects and advantages in view, the invention resides more particularly in the novel combination, formation and arrangement of parts herein- 30 after described and pointed out in the appended claims.

In the drawings:

Figure 1 is a front elevational view of my 35 improved engine starter mechanism, the fan being removed from that shaft of my mechanism on which it is adapted to be carried.

Fig. 2 is a vertical sectional view through 40 the starter mechanism on the line 2—2 of Fig. 1, showing the engine in dotted lines.

Fig. 3 is a transverse sectional view on the line 3—3 of Fig. 2.

Fig. 4 is a transverse sectional view on the line 4—4 of Fig. 2 showing more particularly the method of keying the shaft 45 sprocket thereto.

Referring now more particularly to the accompanying drawings, 5 designates the main shaft of an engine 6 shown in dotted lines, and 7 designates the usual water manifold which extends forwardly at the top of the engine.

My improved engine starter mechanism is carried at the front of the engine and comprises a bracket including the body wall 8

and outstanding side walls 9 taperingly enlarged in width toward their lower ends. The upper portion of the body plate is provided with an aperture 10 adapted to fit over the water manifold 7 and is provided 60 with apertures 11 at the sides of the first aperture adapted to receive the securing bolts 12, normally used to fasten the manifold to the engine body. The starter mechanism includes a sprocket chain trained about 65 a shaft carried by the bracket and about the engine shaft, and to adjust the tension of this chain, the manifold opening 10 of the bracket and one of the openings 11 are longitudinally elongated whereby to permit an 70 angular adjustment of the bracket to vary the distance between the shafts mentioned, the bracket being retained in a desired position by the clamping action of the bolts 12. To hold the lower end of the bracket spaced 75 from the engine body to insure a proper forward position of the bracket, a spacing bolt 13 is threaded in the lower end of the bracket and abuts the lower end of the engine body, this bolt obviously providing for adjustment to compensate for possible variation of 80 thickness of the securing lugs of the water manifold which serves to space the upper portion of the bracket from the engine body.

As in my said previous patent, motion is imparted to the starter mechanism by means of a cable 14 wound on a cable drum 15 which has its hub keyed on a shaft 16 journaled in a projected portion of one of the 90 side walls 9 of the bracket and fixed on the inner end of the shaft is a beveled gear wheel 17 which is disposed in a cutaway portion of the body wall 8 of the bracket and which meshes with a beveled gear 18 having its 95 hub portion journaled in a bearing 19 carried by the body wall of the bracket, this hub portion serving incidentally to journally support the inner end of the main shaft 20 of a starter mechanism. The outer end of 100 the shaft 20 is journaled in a bearing plate 21 supported by securement to the outer portions of the side walls 9 and fixed on the shaft 20 between the bearing plate 21 and the gear 18 is a sprocket wheel 22, about which 105 is trained a sprocket chain 23 trained also about a sprocket wheel 24 on the main engine shaft 5. The beveled gear 18 is provided with a laterally turned peripheral flange portion which rotatably nests within 110

a correspondingly flanged portion of a ratchet wheel 25 which has its teeth disposed on the outer periphery of its flange portion and adapted for co-action with a spring urged pawl 26 slideable in a boss 27 projecting outwardly from one of the side walls 9, it being noted that the diameter of the ratchet wheel 25 is slightly less than the space between said side walls.

10 For rotating the main shaft 20 and consequently the engine shaft 5 upon rotation of the beveled gear wheel 18 the shaft 20 has provided thereon within the inclosed space formed by the wheels 18 and 25 a peripherally toothed ratchet wheel 26' which has its teeth engageable by a pawl 27' pivoted to the gear wheel 18 and resiliently urged to said engagement by a spring 28 secured to the flange portion of the wheel.

15 Thus by the structure above described, pulling movement of the cable to rotate the drum 15 will cause a cranking rotation of the engine shaft 5, and upon said engine shaft being started, independent movement 20 thereof is permitted by means of the pawl 27' and ratchet wheel 26'. To rewind the cable upon the drum 15 to adapt the mechanism for subsequent cranking actuation a spiral spring 29 has its outer end secured at 30 to 25 the adjacent bracket wall 9, and is provided at its inner end with a laterally turned portion engageable in a recess 30 in the hub of the cable drum shaft.

As in my said previous patent, a means is 30 provided for holding the pawl 27' in retracted position upon driving operation of the engine shaft and upon the possible occurrence of back-fire, this means comprises a plurality of inwardly projecting tongues 31 carried by the sprocket wheel 25 and disposed in regularly spaced relation about the ratchet wheel 26', and a corresponding series of tongues 32 carried by an annular plate 33 rotatably inset in the adjacent side face 35 of the sprocket wheel 25, rotation of the plate 33 with respect to the wheel 25 being limited by an inwardly projected lug 34 movable between a pair of adjacent tongues 31. The relation of the tongues is such that 40 45 when said tongues are disposed in radially aligned position the pawl 27' may move therebetween to engage the sprocket wheel 26', and when said tongues are relatively moved they so inclose the sprocket wheel as to prevent engagement of the pawl therewith.

50 Thus by referring more particularly to Fig. 3 it is noted that upon the occurrence of back-fire, the shaft 20 and consequently the gear 18 and cable drum will be momentarily 55 rotated by the force of back-fire. Upon movement of the pawl 27' adjacent a pair of tongues 31 and 32 however, said pawl will be cammed out of engagement with the ratchet wheel thereby and will exert a dragging movement on the tongue 32 which will

move the ring 33 and consequently all of the tongues 32 to a position shielding the ratchet wheel 26 which may then freely rotate without imparting any motion to the cable drum. The tongues 31 and 32 are 60 also operative, upon the engine being started, since at the completion of cranking movement of the mechanism the spring 29 re-winds the cable 14 on the cable drum 15 which procures a consequent movement of 65 the gear wheel 18 and its pawl 27', and in this free movement of the pawl it exerts a dragging action on the tongues 32 to again shield the ratchet wheel and thus permit free driving rotation of the shaft 20. Thus 70 the shaft 20, which is disposed in substantially the position of the fan shaft of an automobile engine and the usual fan 35 of the engine is carried on this shaft.

In fixing the sprocket wheel 24 on the engine shaft the usual opening 36 is utilized which normally receives the locking pin of the fan shaft pulley. Fitted on the engine shaft is a sleeve 37 having an out-turned flange at its inner end and passed through 80 this sleeve and through the opening 36 is a locking pin 38 which has its ends projected outwardly of the sleeve and engageable in recesses 39 formed in the sprocket wheel 24 which is fitted over the sleeve. These parts 85 are retained in assembled relation by a follower sleeve 40 which is threaded on the sleeve 37 and which holds the sprocket wheel against the flange of said sleeve 37, and formed on the outer end of the follower 90 sleeve are a series of clutch teeth engageable by the usual manual cranking means of the engine.

From the foregoing description, it is thus seen that I have provided a starting mechanism which may be associated with an engine in a manner which is most convenient and economical, particularly with respect to the elimination of parts directly associated with the main shaft of the engine, since I 105 combine the usual fan shaft with the main shaft of the mechanism.

While I have shown a preferred embodiment of my invention, it will be understood that various changes and modifications to 110 meet differing conditions of use may be resorted to without departing in any manner from the spirit of my invention as interpreted by the appended claims.

What is claimed is:

1. The combination with an engine including a drive shaft, of a second shaft journaled parallel to said drive shaft, a connection between said shafts, a gear wheel on the second shaft provided with a laterally 125 turned peripheral flange, a ratchet wheel provided with a laterally turned flange disposed about the flange of the gear wheel, manual means for rotating said gear wheel, and means disposed within the inclosed space 130

formed by said wheels for initially rotating the drive shaft upon the rotation of said gear wheel.

2. The combination with an engine including a drive shaft of a second shaft mounted thereabove, a releasable drive means for the second shaft, a sprocket wheel on the second shaft, a sleeve on the engine shaft having an up-turned flange at one end, a locking pin passed through the sleeve and shaft with its end projected outwardly of the sleeve, a sprocket wheel mounted on the sleeve and provided with recesses receiving the projected ends of the said pin, a follower sleeve threaded on the first sleeve, clutch teeth formed on the outer end of the follower sleeve and a chain trained about both said sprocket wheels.

3. An engine starter mechanism including a journaled shaft, a gear wheel on said

shaft provided with a laterally turned peripheral flange, means for rotating said gear wheel, a ratchet wheel provided with a laterally turned tooth carrying flange disposed about the flange of the gear wheel, a second ratchet wheel disposed intermediate the first named wheels, a pawl pivoted to the gear wheel for co-action with the second ratchet wheel, pawl retracting tongues carried by the first ratchet wheel and a second pawl for co-action with the teeth of the first ratchet wheel.

In testimony that I claim the foregoing I have hereunto set my hand at Racine, in the county of Racine and State of Wisconsin, in the presence of two witnesses.

HENRY R. SIEVERKROPP.
